CLAIM

The ornamental design for a multi-compartmented cooling system, as shown and described.

DESCRIPTION

FIG. 1 is a left side front perspective view of a multi-compartmented cooling system showing my new design;

FIG. 2 is a top view thereof;

FIG. 3 is a front elevational view thereof;

FIG. 4 is a left side elevational view thereof;

FIG. 5 is a right side elevational view; and,

FIG. 6 is a rear view thereof.

The unornamented bottom is not disclosed.

FIG. 1

FIG. 3

FIG. 2

FIG. 5

FIG. 4

FIG. 6
